UNITED STATES PATENT OFFICE

2,485,009

OVERLOAD RELEASE FOR POWER PRESSES

Jules Muller, Chicago, Ill., assignor to E. W. Bliss
Company, Detroit, Mich., a corporation of
Delaware

Application October 22, 1947, Serial No. 781,398

1 Claim. (Cl. 74—581)

1

This invention relates to shape-forming, blanking or drawing presses, and has particular reference to pressure relieving means for the forming or drawing parts when a predetermined overload pressure has been developed thereby.

In the use of presses of this character the work-shaping or blanking parts, which are mechanically adjustable as to travel of the work coacting parts, are subjected at times to varying overloads occasioned, for instance, by variations in the hardness of the work material or in the thickness thereof, which may result in severe damage to the press parts and dies and cause spoilage of the work. These severe overloads frequently cause breakage or bending of the press parts as well as stalling, resulting in costly repairs and the loss of production.

The object of the present invention is to prevent or reduce such failures and the resultant cost of repairs and loss of production to a minimum by interposing a novel, simple and efficient safety unit in the pressure producing linkage or connections of the press. This unit is of a nature to be interposed in practically any pressure applying linkage of the press and does not become operative to relieve an overload condition until a predetermined pressure is applied to the link.

As an illustration, the four-point blank holder of a mechanical press rated at 500 tons will apply, through proper linkage, 125 tons at each corner connection of the blank holder. The amount of travel of the blank holder is adjustable according to the thickness of the material processed. When the thickness of the material exceeds that for which the travel to produce the desired pressure is adjusted, an overload will be imposed on the press. Similarly, a press with rated plunger capacity of say 100 tons single point will be subjected to a large overload on the pressure producing linkage when by accident two or more thicknesses of material, or material of greater thickness or hardness, or of higher physical properties than those for which the press is set, are introduced into the work performing point of the press.

The invention is fully described in the following specification, and two embodiments thereof are illustrated in the accompanying drawings, in which—

Fig. 1 is a front elevation of a press embodying the invention; Fig. 2 is an enlarged section on the line 2—2 in Fig. 1; Fig. 3 is a perspective view in separated form of three of the pressure rings used in connection with the invention, with parts

2

broken away, and Fig. 4 is a side view of a different form of linkage embodying the invention, with parts in central longitudinal section.

Referring to the drawings, Fig. 1 illustrates a conventional form of power press for sheet metal stamping work, or the like, and includes a blank holder 1 operating in frame guides 2. The blank holder has the required reciprocatory movement imparted thereto from an overhead operating means by a plurality of links 3, usually four in number, one at each corner of the blank holder, as well understood in the art, and the yielding means embodying the invention is interposed, in the present instance, between each link and the respective corner of the blank holder.

This means, in the illustrated embodiment thereof shown in Fig. 2, comprises a plunger head 5 with which the respective link 3 has pivoted or universal thrust connection and which has a stem 6 projected downward therefrom through an opening 7 in a registering portion 8 of the blank holder. This stem is threaded and carries a top thrust nut 9 above the portion 8 and a hollow thrust nut 10 below said portion. The stem 6 is freely encircled between said thrust parts with a thrust sleeve 11 having an annular radial flange or enlargement 12 at its upper end which receives the thrust of the part 9. The lower end of this sleeve projects below the blank holder part 8 and receives a nut 13 intermediate the said part and the nut 10, so that, in the present instance, the blank holder part 8 is supported by the stem 6 and nut 10 through the medium of the nut 13.

The blank holder opening 7 has an enlargement 7a above its lower end portion, which latter guidingly fits the sleeve 11, and its upper end is further enlarged, as at 7b, to receive and guide the axial movements of the sleeve enlargement 12, with the enlargement normally spaced from the bottom of the portion 7b.

The sleeve 11, at its upper end adjacent to the enlargement 12, is provided with a downwardly facing conical annular seat 14 concentric to the sleeve axis, and in the bottom of the opening enlargement 7a is an upwardly facing conical collar 15. Surrounding the sleeve 11 intermediate the conical seats 14 and 15 are an inner set of spaced rings 16 and an outer set of spaced rings 17, which latter alternate with the rings of the inner set with the end or top and bottom rings of the outer set in endwise thrust engagement with the respective conical seats 14 and 15. The inner rings 16 closely hug the sleeve 11 while the outer rings 17 are preferably spaced

slightly from the sleeve, and the meeting corner portions of the rings of both sets are beveled or tapered so that the rings of one set will have tapered or wedge-like coaction with those of the other set. It is thus apparent that when longitudinal pressure is applied to the set of rings having engagement with the conical seats 14 and 15, there will be a tendency for the rings of such set to radially expand due to the coaction of the tapered surfaces. When such expansion takes place under predetermined overload pressures, the sleeve 11 will be permitted to move inward a slight distance relative to the part 8 into which it projects, whereby to compensate for the overload pressure.

When the parts of the yielding pressure means have been assembled as above described, the outer ring elements as a set are axially compressed and at the same time are radially expanded to suit the pressure to be applied to the blank holder through such connection during normal operation of the press. Should an overload beyond such normal operating pressure be applied, from any cause, through the connection to the blank holder, as by increased thickness of material acted on or increased hardness thereof, the rings of the outer set will be relatively compressed axially of the sleeve 11 and, due to the action of the tapered surfaces 14 and 15 on the end rings of the outer set and tapered coaction of the outer rings with the tapered surfaces of the inner rings, the rings 17 will be radially expanded, thus allowing the safety connection to yield sufficiently to prevent any undue strain to be imposed on the press parts. To render the rings 16 and 17 yielding, they are made of suitable spring steel.

The safety connection is given the desired tension to withstand yielding under normal loads by an adjustment of the nuts 9 and 10 on the stem 6 and an adjustment of the nut 13 on the sleeve 11, as is apparent, and the connection then will not yield under normal operating conditions, but only when a predetermined overload pressure is applied. The elasticity in the rings is sufficient to cause them to return to their normal contracted positions for which adjusted when relieved of the overload condition and to return the parts of the connection to their normal positions for which adjusted. It will be understood that while the yielding connection has been shown as including two inner rings 16 and three outer rings 17, the rings may be increased or diminished in number to suit the particular application. The space 7a in which the rings are disposed is filled with oil.

In the modification of the yielding connection shown in Fig. 4, 20 designates a part of the linkage or other pressure applying means of the press, 21 a part to which pressure is applied and which may be attached to or comprise, for instance, a part of the press blank holder with the connection therebetween comprising the invention.

The part 21 has a stepped socket 22 therein in line with the thrust action of the part 20 and forming near its bottom the annular shoulder 23 and near its top the annular shoulder 24. The yieldingly mounted thrust sleeve 25 is inserted into the socket 22 in radially spaced relation to the socket wall and terminates at its inner end short of the shoulder 23. The outer end of the sleeve 25 has a radial flange or enlargement 26 fitting into the outer enlarged end of the socket and held in predetermined spaced relation to the shoulder 24 by screws 27 loosely inserted through apertures

therein and threaded into said shoulder. The screw heads serve as stops to limit the outward movements of the sleeve relative to the part 21 on which mounted. In the angle between the sleeve 5 and its flange is provided an annular tapered surface 28 concentric to the sleeve axis, and mounted on the sleeve between this taper and the socket shoulder 23 are, in the present instance, two inner rings 29 with tapered outer edges and an end ring 30 seating on the shoulder 22 and having a single tapered surface 31 facing the sleeve taper 28. A plurality of rings 32 forming an outer set alternate with and have tapered inner edges bearing against the registering tapered edges of the 10 inner rings 29 and the respective tapered surfaces 28 and 31, as shown. The rings 32 resist an inward movement of the sleeve 25 relative to the socket shoulder 23 and ring 30 seating thereon, and upon the application of a predetermined 15 overload pressure to the sleeve 25, the rings 32 are relatively contracted in an axial direction and thereby caused to ride out on the coacting tapered surfaces and to radially expand the same as in the first-described form.

23 The inner end of the sleeve 25 is threaded internally to a nipple 33 that projects through the ring 30 and shoulders thereunder. It is apparent that either an inward adjustment of the sleeve 25 by a tightening of the screws 27 or an adjustment 20 of the nipple 33 relative to the sleeve will adjust the tension of the yielding connection. The sleeve 25, nipple 33 and interposed rings 29, 30 and 32 form an assembly which may be inserted in or removed as a unit from engagement 25 with the member 21.

The member 20 has a bar or rod 35 threaded therein in the line of thrust for adjustment relative thereto, and this is shown as having an enlargement 36 shouldering against the outer end 40 of the sleeve 25 or its flange 26. A stem 37 projects from this enlargement freely into the sleeve 25 and has its free end reduced and freely projected through the nipple 33 and engaged at its end by a nut 38 that bears against the outer end 45 of the nipple so that the yielding assembly unit is carried by the member 35 in clamped relation between the enlargement 36 and said nut.

In either form of the invention the yielding connecting means may be reversed with respect 50 to the pressure applying and pressure receiving elements, as no difference in operation or result would thereby be effected. The only difference would be that the sleeve 11 in one case and 25 in the other case, in one position of the yielding 55 unit, would serve as the pressure applying element and in the reverse position thereof would serve as the pressure receiving element.

While in both forms the yielding characteristic under abnormal load conditions has been 60 described as taking place in the outer set of rings by expansion thereof, it is apparent that under high pressures there may be and probably is some compression of the inner rings and other parts with which the outer rings coact. It is, of course, apparent that the inner rings may be made of very hard material which is non-compressible under pressure conditions encountered in stamping or drawing presses, so that all of the yieldability of the connection takes place in the outer set of rings. Ordinarily, however, in practice there will probably be some give or yieldability in all coacting tapered surfaces with that of the outer rings the greater.

I wish it understood that my invention is not limited to any specific construction, arrangement

or form of the parts, as it is capable of numerous modifications without departing from the spirit of the claim.

Having thus described my invention, what I claim as new, and desire to secure by United States Letters Patent, is:

In a pressure applying linkage for a power press, a linkage part through which thrust is applied and a thrust-receiving part, said thrust applying part having a stem, a thrust sleeve in 10 thrust coaction with said thrust applying part, said sleeve receiving said stem and having a radial flange adjacent to the thrust part, inner and outer sets of wedge rings encircling said sleeve with the outer set alternating with those of the inner set and having wedge coaction whereby 15 relative axial movements thereof cause expanding action of the outer rings, one of said outer rings having a tapered seat on the flange portion of said sleeve, means anchored to the free end of

20 said stem and having tapered thrust coaction with an end ring of said outer set, said means having thrust coaction with said thrust-receiving part whereby a yielding of said rings under thrust action permits relative inward movements of said sleeve and thrust-receiving part, said thrust-receiving part cooperating with the flange of said sleeve to form a housing for said rings.
